EMERGENCY VALVE STRUCTURE FOR
LOCOMOTIVE BOILERS AND THE LIKE

Westy F. Matson, Newton, Kans.

Application October 24, 1942, Serial No. 463,240

2 Claims. (Cl. 251—26)

This invention relates to an emergency valve structure for locomotive boilers and the like, and it is particularly an object of the invention to provide means whereby in the event of an accident, or for any other cause, the engineer or other person can readily cut off the supply of steam or kindred fluid.

It is also an object of the invention to provide a valve of this kind which can be used with equal facility in connection with a portable or stationary boiler, and wherein is provided manually operated means for shutting off the steam or other fluid in the event of an emergency, and thereby avoiding injury to the engineer or other person.

The invention consists in the details of construction and in the combination and arrangement of the several parts of my improved emergency valve whereby certain important advantages are attained, as will be hereinafter more fully set forth.

In order that my invention may be the better understood, I will now proceed to describe the same with reference to the accompanying drawing, wherein:

Figure 1 is a view in elevation and of a diagrammatic character illustrating an emergency valve structure embodying the invention.

Figure 2 is an enlarged sectional view taken substantially on the line 2—2 of Figure 1, looking in the direction of the arrows, and

Figure 3 is an enlarged sectional view taken substantially on the line 3—3 of Figure 1, looking in the direction of the arrows.

As disclosed in the accompanying drawing, C denotes a box-shaped chest preferably constructed of all metal and which is riveted, bolted or otherwise rigidly anchored in desired position on the head 1 of a boiler, or such other location as may be preferred. This chest C is preferably elongated and may be horizontally disposed or vertically arranged as preferred. In the present embodiment of the invention the chest C is horizontally arranged and one end portion provided exteriorly thereof with a passageway or conduit 2 in direct communication with the boiler B, and also in communication with the chest C are the usual pipes 3 leading to the steam or fluid consuming devices. This passageway or conduit 2 is formed within an outstanding part a rigid with the back wall of the chest C, said part extending within the boiler through a suitably provided elongated opening b provided in the head 1 of the boiler. This passageway or conduit 2 has its outer end opening within the boiler while the opposite end is in communication with the in-

terior of the chest C through the port or opening 4 provided in the back wall of the chest C.

The passageway or conduit 2 is in direct communication with the chest C through a port 4 in which is threaded or otherwise engaged a valve core or seat 5 with which coacts a valve member 6 arranged within the adjacent end portion of the passageway or conduit 2. This valve member 6 is urged toward its seat 5 by an expansible coil 10 spring 7 of requisite tension interposed between the valve member 6 and the adjacent wall of the passageway or conduit 2. This adjacent portion of the conduit or passageway 2 is formed to provide a well 8 to allow for sufficient movement 15 of the valve member 6 and an effective placement of the spring 7.

The valve member 6 is mounted upon the inserted end portion of an elongated stem 9 which extends through the port 4 and through a guide bushing 10 threaded through a properly positioned opening 11 in the outer face wall of the chest C. This stem 9 in the present embodiment of the invention is of a length to have its outer end portion at all times disposed beyond the outer end of the applied guide bushing 10 so that the same may have effective contact with the trigger head or block 12 for holding the valve member 6 in open position and the spring 7 under sufficient tension to move the valve member 6 into closed position upon release of the head or block 12 from the stem 9. The trigger head or block 12 is provided with an upstanding trip lever 14 of desired length and to the upper end portion of which is connected, as at 15, the flexible members 16 leading to such locations desired. When used in connection with a train there are preferably three of such flexible members, two leading to the sides of the engine cab and a third one extending along the train so that the same can be readily pulled by the brakeman at any point along the train to swing the trigger head or block 12 to release the valve 6.

As is clearly illustrated in the accompanying drawing, the trigger head or block 12 is supported 45 for rocking movement between the outstanding lugs 17 carried by the outer face of the guide bushing 10 through the medium of a pin 18. This mounting for the trigger head or block 12 is to one side of the stem 9 a distance sufficient to 50 allow the inner or working end of the head or block 12 to only partially overlie the adjacent end of the stem 9 so that but slight rocking movement of the head or block 12 will be required to release the stem 9. It is also preferred, as illustrated in the accompanying drawing, that the

inner or working end of this block or head 12 be inwardly beveled thereacross, as at 19, to further facilitate quick disengagement of the point or tip of the head or block 12 which is formed by such beveling from the stem 9.

The inner wall of the chest C, as herein disclosed, is provided with an inwardly disposed block 20 in which is slidably received a gate valve 21 which is adapted to be moved outwardly to intersect the passageway or conduit 2 in advance of the port 4 so that flow of steam or kindred fluid may be readily shut off when it is desired to reset into open position the valve member 6. This gate valve 21 carries a stem 22 of a length to extend outwardly and beyond the outer wall of the chest C whereby the valve 21 may be readily shifted into either its closed or open position.

The back wall of the chest C, or that wall provided with the port 4, is also provided with a port in registry with a corresponding port in the head 1 of the boiler B and which constitutes an emergency passage and which is normally closed by the inwardly opening valve member 23. This valve member 23 carries a stem 24 of a length to extend through and beyond the front face of the chest C so that the valve member 23 may be readily opened or closed.

In view of the foregoing, it is believed to be readily apparent that the emergency valve structure as herein embodied constitutes a unit which can be readily applied in working position after the proper openings have been made in the boiler head 1 or kindred wall.

It is to be further stated that in practice it is desired that certain of the flexible members 16 extend to and be secured to the tender of the locomotive so that in the event the engine and tender should separate when a train is in motion, the head or block 12 will be operated to release the stem 9. While the invention as herein disclosed is especially advantageous for use in connection with a locomotive, it is to be stated that it can also be used in connection with a marine engine or with any other type of portable or stationary engines using steam, compressed air and the like.

From the foregoing description it is thought to be obvious that an emergency valve constructed in accordance with my invention is particularly well adapted for use by reason of the convenience and facility with which it may be assembled and operated.

I claim:

1. The combination with a wall of a fluid receptacle, the wall having an opening therethrough, of a valve unit consisting of a chest adapted to be secured to said wall over the opening, a chambered part integral with the chest and adapted to extend through the opening into the receptacle, a port opening between the cham-

bered part and the chest and forming a valve seat, a port opening through said chambered part, means forming a valve stem guide secured in a wall of the chest in alignment with said port, a pair of spaced ears carried by said guide outside the chest, a valve stem slideable through the guide and having an end extended outwardly between said ears, the other end of the stem extending through said port into the chambered part, a valve carried in the chambered part on the said other end of the stem for engagement on the seat, resilient means urging the valve toward said seat, a pivot supported between said ears at one side of the axis of the valve stem, a trigger head supported on said pivot for oscillation, the head having a beveled end face forming a pointed tip having detachable engagement with the adjacent end of the stem to hold the valve stem against the action of said resilient means, said beveled face facilitating the free outward movement of the stem when said tip is moved inwardly against and across and out of engagement with the said end of the stem, and a control lever carried by said head for oscillating the same to release the stem.

2. The combination with a wall of a fluid receptacle, the wall having an opening therethrough, of a valve unit consisting of a chest adapted to be secured to said wall over the opening, a chambered part integral with the chest and adapted to extend through the opening into the receptacle, a port opening between the chambered part and the chest and forming a valve seat, a port opening through said chambered part, means forming a valve stem guide secured in a wall of the chest in alignment with said port, a pair of spaced ears carried by said guide outside the chest, a valve stem slideable through the guide and having an end extended outwardly and terminating between said ears, the other end of the stem extending through said port into the chambered part, a valve carried on the other end of the stem in the chambered part for engagement on said seat, resilient means urging the valve toward said seat, a pivot supported between the ears to one side of the axial center of the valve stem, a trigger head comprising a block-like body supported on said pivot for oscillation, the head being beveled in a plane oblique to the length of the stem to form a pointed tip having engagement against the adjacent end of the stem whereby upon oscillation of the head in one direction the tip will move off of the stem end permitting the stem to move outwardly across the beveled portion of the head, and means connected with the head for facilitating the oscillation of the head to disengage the tip from the stem.

WESTY F. MATSON.
